(57) **CLAIM**

The ornamental design for an advertising display, as shown and described.

DESCRIPTION

FIG. 1 is a front, right and top perspective view of an advertising display, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right-side elevation view thereof.

FIG. 7 is a top plan view thereof.

FIG. 8 is a bottom plan view thereof.

FIG. 9 is an enlarged detailed view of encircled area 9 in FIG. 1.

FIG. 10 is an enlarged detailed view of encircled area 10 in FIG. 1; and,

FIG. 11 is an enlarged detailed view of encircled area 11 in FIG. 2.

The broken lines shown in the drawings are included for the purpose of illustrating portions of the advertising display that form no part of the claimed design.

1 Claim, 11 Drawing Sheets
